UNITED STATES PATENT OFFICE.

ANDREW P. PANOS, OF SHREVEPORT, LOUISIANA.

BELT.

Application filed November 22, 1921. Serial No. 517,061.

To all whom it may concern:

Be it known that I, ANDREW P. PANOS, a citizen of the United States, residing at Shreveport, in the parish of Caddo and State of Louisiana, have invented a new and useful Belt, of which the following is a specification.

This invention aims to provide a novel form of belt, adapted to be placed about 10 the body of the wearer, novel means being carried by the belt for upholding a pair of pantaloons or any other garment.

It is within the province of the disclosure to improve generally and to enhance the 15 utility of devices of that type to which the invention appertains.

With the above and other objects in view, which will appear as the description proceeds, the invention resides in the combination and arrangement of parts and in the details of construction hereinafter described and claimed, it being understood that, within the scope of what is claimed, changes in the precise embodiment of the invention 25 shown can be made without departing from the spirit of the invention.

In the accompanying drawings:—

Figure 1 shows in front elevation, a belt constructed in accordance with the invention; Figure 2 is an elevation disclosing one 30 of the end members of the belt, parts being broken away; Figure 3 is an elevation showing the other of the end members of the belt; Figure 4 is an elevation wherein the member shown in Figure 2 is viewed edge-wise; Figure 5 is a cross section on the line 5—5 of Figure 3; Figure 6 is a plan of the member shown in Figure 2; Figure 7 is an elevation disclosing the auxiliary support; 35 Figure 8 is an elevation showing one of the main supports or spacers.

In carrying out the invention there is provided an end member 1, shown in detail in Figures 2 and 4, and, preferably, made of 45 metal, the end member comprising a tubular body 2 from which wings 3 project, the wings having pairs of openings, there being any desired number of these openings, depending upon the number of strips which 50 form the body encircling member of the belt. The body 1 is provided with outwardly extended bosses 5 defining seats 6 in the body 2. In the body 2, key hole slots 7 are formed, the reduced portions of the key 55 hole slots extending into the bosses 5, as shown in Figure 4.

The device includes an end member 8, constructed, in general, like the end member 1, and comprising a tubular body 9 and wings 10, the wings having any desired number of 60 openings 11. Studs 12 project from the body 9 and have enlarged heads 14. Lateral studs 15 project from the head 9 and are supplied with enlarged heads 16.

The body encircling member of the belt 65 is denoted by the numeral 17 and may be made up of any desired number of strips 18, looped at their ends, as shown at 19, through the openings 11 of the end member 8, and through the openings 4 of the end member 70 1, the ends of the strips 18 being attached to the main portions of the said strips by securing elements 20.

Spacers or supports 21 are distributed around the body encircling member 17, the 75 spacers preferably being in the form of plates, as shown in Figure 8, each spacer having openings 22 for the reception of the constituent strips 18 of the body encircling member 17, the construction being such that 80 the spacers may be shifted circumferentially of the belt. Each spacer 21 is provided at its upper end with a reduced neck 23. A seat 24 is formed in the end of the neck 23, the neck terminating in a hook 25 overhanging the seat 24.

An auxiliary support 26 is provided, the same having a seat 27 in its upper end, and being provided with a hook 28 overhanging the seat. Sinuous key hole slots 29 are 90 fashioned in the auxiliary support 26. The key hole slots 29 are adapted to receive the lateral studs 15 on the member 8 and, thus, the auxiliary support 26 may be mounted on the member 8, removably, as shown in Figure 95 1 of the drawings. The ends of the belt may be united by inserting the studs 12 of the member 8 into the key hole slots 7 of the member 1, relative movement between the members 1 and 8, in the direction of their 100 length, being brought about, until the heads 14 of the studs 12 are received in the seats 6. Thus, the ends, of the belt may be united detachably.

The belt is placed about the body of the 105 wearer, and the connections which unite the suspender buttons with a pair of pantaloons are engaged in the seats 24 and 27, beneath the corresponding hooks 25 and 28, the pantaloons thus being sustained upon the body 110 of the wearer without the use of suspenders. Owing to the particular construction dis-

closed, as for instance, at 24—25, the buttons on the trousers will be held in place securely to the belt and an accidental detachment will not be likely to take place. As hereinbefore explained, the spacers or supports 21 may be shifted longitudinally of the belt so as to cooperate properly with the buttons on the pantaloons.

Having thus described the invention, what is claimed is:—

A belt comprising end members and means for connecting the end members releasably, main supports shiftable longitudinally of the belt, and extended above the

belt, an auxiliary support overlapped on 15 one end member and extended thereabove, all of the supports being provided at their upper ends with button-holding elements, and means for connecting the auxiliary support releasably with said end member. 20

In testimony that I claim the foregoing as my own, I have hereto affixed my signature in the presence of two witnesses.

ANDREW P. PANOS.
